UNITED STATES PATENT OFFICE.

LORENZO M. MUMFORD AND ROY F. MILLER, OF BOLIVAR, PENNSYLVANIA.

BRICK-ENGOMBING MACHINE.

Application filed March 19, 1927. Serial No. 176,670.

This invention relates to apparatus for partially veneering or coating brick. This process is sometimes called engobing.

The objects of the present invention are 5 to provide improved means for partially coating bricks with a plastic material of a higher grade than that used for making the body of the bricks.

An object of the invention is to so position the engobing apparatus with respect to apparatus for producing a clay bar that the bar may be freely exposed for inspection and correction before passage through the engobing apparatus, so that an operator may 15 correct any deformities in the clay bar, may remove it, or for any purpose have access to the clay bar before it enters the engobing apparatus.

Another object of the invention is to provide improved feeding mechanism for supplying engobing material to the casing where it is to be applied to the clay bar, and particularly to provide constantly operative means for maintaining a constant 25 pressure upon the engobing material so that it may be uniformly fed to and around the clay bar, and applied thereto with sufficient but cushioned pressure to insure that a uniformly coated clay bar is produced. To this 30 end compressed air is used to drive the engobing material.

Another object is to supply the engobing material so that it will be forced directly against the sides as well as the top of the 35 clay bar.

Another object is to provide means for an uninterrupted supply of engobing material, so that there need be no interruption in the formation and coating of the bricks.

40 Referring to the drawings, Fig. 1 shows in front elevation an arrangement of our apparatus; and Fig. 2 shows a partial vertical section on the line II-II of Fig. 1.

The veneering or engobing of brick is not 45 new. It has been practiced for many years. Various means of applying the coating of veneering material to the clay bar have been provided. These however have been open to the objection that they were placed immediately at the outlet of the apparatus for forming the clay, consequently there was no access on the part of an operator to get at the clay bar before it entered the engobing casing. A further objection has been that 50 the feed of the engobing material to the casing wherein it is applied to the bar has

been by mechanically driven members so that often there was too great or too little pressure, with resultant lack of uniformity 60 of the product.

These disadvantages are overcome and other advantages are secured by means of the apparatus now to be described.

Referring to the drawings, and particularly Fig. 2, the outer casing 1 of a standard auger machine is indicated. It will be understood that suitable brick forming materials are mixed at points not shown, and fed to the casing 1, and forced therethrough by means of the screw conveyor 2. The 70 plastic material passes out the orifice 3, in the form of a clay bar 4, which is in cross-sectional area equal to the face of a brick. When this bar is cut across at distances equal to the thickness of a brick, brick 75 blanks are produced. These are then dried and burned, and sold for commercial uses.

To this standard form of auger machine, which is not new with us, and not claimed as a part of our invention, we apply an extended plate or support 5, upon which the clay bar is run out. At the outer end of this support 5 and spaced a material distance from the orifice 3, a casing 6 is provided, for 80 engobing or veneering the clay bar as it 85 passes therethrough.

This casing 6 has an inner receiving opening 7, through which the clay bar enters. The walls of this opening 7 are tapered inwardly, so that there is free space for the 90 clay bar to enter the opening, but it is slicked off or sized as it passes the inner edge of the opening 7 and on into the interior chamber 8 formed within the casing. At the other side of casing 6 a similar aligned 95 second opening 9 is provided through which the clay bar passes out of the casing. This opening 9 likewise has its walls tapered from the inside towards the outside, so that at the outer edges of the openings the 100 orifice is of the size desired for the cross-sectional dimensions of the finished clay bar itself. The chamber 8 is larger in cross-sectional area than the clay bar, so that a space is provided above and at each side of the 105 clay bar, surrounding it on the three exposed faces.

Tanks 10 and 11 are provided for storing engobing material of suitable plasticity for applying to the clay bar. The tops of these 110 tanks are closed, they are air tight, and into them extend pipes 12 and 13, controlled by

valves 14 and 15, respectively. These pipes are connected by a branch 16 to a source of air pressure, as for example a pressure storage tank, not itself shown. The pipe 16 has in it a pressure reducing valve P for the purpose of maintaining a constant pressure in the pipes 12 and 13 for application to the tanks. This secures constant feed pressure regardless of variation in the source of pressure. Such pressure regulating valves are well known and are not a part per se of this invention, therefore the one indicated is not described in detail. A pressure indicating gage 17 is provided to show pressure on the tanks.

At their lower ends the tanks 10 and 11 have outlet pipes 18 and 19, controlled by valves 20 and 21, respectively, leading to a horizontal pipe 22. From the pipe 22 extend branches 23, 24, and 25, which lead respectively into the side, top and other side of the engobing casing 6.

In operation, one of the valves 20 or 21, and one of the valves 14 or 15, is closed, and engobing material is supplied from only one of the tanks 10 or 11, while the other is being filled, or held as a reserve. By this arrangement the continuity of applying coating to the clay bar need never be interrupted, under normal conditions.

The operation of this apparatus is as follows:

The auger machine in the casing 1 forms and continuously extrudes a clay bar 4. This passes in the converging opening 7 of the engobing casing 6, through that casing and out converging opening 9.

Engobing material of suitable plasticity from tank 10 or 11, is fed through the pipes 22, 23, 24 and 25, to fill the chamber 8, surrounding the clay bar inside the casing 6. Air pressure from the pipe 16 is applied to a follower F on top of the engobing material in the tank, and therefore maintains the plastic coating material under constant pressure sufficient to flow it through the pipes and into the engobing chamber 8, and apply it under constant pressure against the clay bar, the material being fed against both sides as well as the top of the bar.

The clay bar is itself moist and is therefore suitable for taking and retaining the coating or veneering of engobing material in a thin closely adhering cover. The converging walls of the opening 9 act as a slicker to take off all excess of engobing material, and to insure that the clay bar will receive a very light squeezed-on coating of the engobing material upon its top and two sides.

After passage from casing 6 the bar is cut transversely to form bricks. The veneering or engobing therefore appears upon the two ends and one face thereof, the other face and the two sides of the brick being uncoated. Obviously a brick is produced that

is capable of being built into a wall with all the appearance of bricks composed entirely of the high quality coating material.

If anything goes wrong with the clay bar after it comes out of the auger machine and before it enters the engobing casing, the trouble is readily apparent to an operator, who has that portion of the clay bar directly under his observation. The deformed portion of the clay bar may be cut off and destroyed, and the new end inserted into the engobing casing, at the will of the operator. While this is being done the valve in the engobing supply line will be closed so that the engobing material will not be unnecessarily extruded through and out of the engobing casing 6 while the clay bar is being removed in its rear.

By using compressed air as the driving force of the engobing material, a constant pressure may be obtained. This is of great importance, since it prevents variation in the pressure used for applying the engobing to the clay bar and results in a uniform product. It insures that at all times the coating will be properly incorporated with or attached to the brick bar under a suitable constant pressure.

Many uses and advantages of this apparatus will be apparent to those familiar with the art.

We claim:

1. Apparatus for engobing brick, comprising means to produce and extrude a clay bar, a casing through which the bar is continuously moved, a source of engobing material connected to said casing, and fluid pressure operated means to force the engobing material into the casing and against the clay bar.

2. Apparatus for veneering or engobing brick, comprising means for continuously producing a clay bar, a support for the clay bar, a casing upon the said support and spaced apart from the said bar producing mechanism, and means to force plastic engobing material into the said casing and against the said clay bar.

3. In a machine or apparatus for veneering brick, the combination with an auger machine adapted to continuously produce a clay bar, of a supporting plate for the clay bar, a casing adapted to envelop the clay bar mounted upon the plate at a distance from the auger machine, a reservoir for holding plastic engobing material, a source of fluid pressure and means to apply it to the top of the engobing material in the tanks, and conduits adapted to convey the engobing material to the casing surrounding the brick bar.

4. Apparatus for engobing brick, comprising a machine adapted to produce a clay bar, a support for the bar beyond the orifice from the said machine, a casing through

which the brick bar is adapted to be extruded, connections from said casing to a reservoir adapted to contain engobing material, and fluid pressure means to force the engobing material from the said reservoir into the said casing and there to apply it to three sides of the clay bar.

5. Apparatus for engobing brick comprising means adapted to continuously produce 10 a clay bar, a plate for supporting said bar, a casing mounted on the plate and spaced away from the bar-producing apparatus, a plurality of storage reservoirs adapted to hold engobing material, valves and conduits 15 whereby the engobing material from any one of said reservoirs may be led to said casing while the others are cut off, and fluid pressure operated means to drive engobing

material from said reservoir to said casing and against the clay bar therein. 20

6. Apparatus engobing brick comprising means for extruding a clay bar, a support for said bar, a casing on said support and adapted to receive the clay bar and permit it to pass therethrough, a source of plastic 25 engobing material, resilient means to force the engobing material from said source into the casing, and conduits from said source leading to the sides and top of the said casing, whereby to force the engobing material 30 directly against each side and the top of the clay bar as it passes through the casing.

In testimony whereof, we hereunto sign our names.

LORENZO M. MUMFORD.
ROY F. MILLER.
